UNITED STATES PATENT OFFICE.

OWEN BULLOCK, OF HEMEL HEMPSTEAD, AND WILLIAM HENRY FORTY, OF BOXMOOR, ENGLAND, ASSIGNEES TO BULLOCK, FORTY AND COMPANY, LIMITED, OF HEMEL HEMPSTEAD, ENGLAND.

SHUTTLE-MOTION FOR LOOMS.

SPECIFICATION forming part of Letters Patent No. 728,158, dated May 12, 1903.

Original application filed March 24, 1902, Serial No. 99,756. Divided and this application filed July 28, 1902, Serial No. 117,379. (No model.)

To all whom it may concern:

Be it known that we, OWEN BULLOCK, residing at Marrows, Hemel Hempstead, and WILLIAM HENRY FORTY, residing at The

5 Woodlands, Boxmoor, in the county of Hertford, England, engineers, subjects of the King of Great Britain, have invented certain new and useful Improvements in Shuttle-Motions for Looms, of which the following is a 10 specification.

This invention relates to shuttle mechanism for looms in which the shuttles are passed to and fro by means of two pusher-rods, one at one side of the loom, the other at the other.

15 According to this invention the shuttle is provided with a spring-clip at each end, and the rods are formed with oblong heads which when turned into one position can pass into and out of the spring-clips without being 20 caught by them, but when turned into another position can be pressed into the clips, but not drawn back from them. The pusher-rods are caused to be moved simultaneously toward one another, and then both of them are simul-

25 taneously drawn back to the sides of the loom. When the rods move toward one another, the head of one rod, which then pushes forward the shuttle in front of it, is in such a position that its head is not caught by the spring-clip 30 at that end of the shuttle which the rod acts against. When the shuttle has been thus pushed half-way across the loom by one rod, the spring-clip at the opposite end of the shuttle passes onto and catches the head of

35 the other rod, and then when both rods are drawn back to the sides of the loom the shuttle is drawn along by this second rod and its movement across the loom thereby completed. At the completion of the shuttle's movement 40 a partial turn is given to both rods to reverse their action when the shuttle has to be passed across the loom in the opposite direction.

In the drawings annexed we have shown 45 shuttle mechanism constructed to act in the above manner applied to a loom for weaving coir mats. In this loom the mats are woven

double, face to face, as has before been proposed, and two shuttles are used, one for the upper ground cloth and the other for the lower one.

Figure 1 is a plan view of so much of a loom having our improvements applied to it as is necessary for enabling the improvements to be fully understood. Fig. 2 is a longitudinal section of the front part of the loom on an 55 enlarged scale. Fig. 3 is a front elevation of the mechanism at one side of the loom for passing the shuttles, the side of the loom-frame being in section. Fig. 4 is a plan view of one of the shuttles and of portions of the 60 two drivers by which it is moved to and fro.

Other parts of the loom besides those required for giving movement to the shuttles are shown in the drawings; but as these other parts are described in another application 65 for patent, Serial No. 99,756, made by us it is unnecessary to describe them in this specification.

In the drawings, A is a cam-shaft revolved continuously by gearing from the shaft A', 70 driven from the driving-shaft A². On it are cams for transmitting motion to various parts of the loom, as described in said other application for patent made by us, Serial No. 99,756. E is another shaft also receiving a continuous 75 revolving movement from the shaft A'. From the ends of the shaft E motion is given to the shuttle-passing mechanism at each side of the loom, as hereinafter described.

The mechanism for crossing the ground-warps of each ground fabric and for crossing the pile-warps may be arranged in any ordinary way. Only the heddles F of this mechanism are shown.

M represents the blades of the reed or comb 85 of the batten. The back of each of the two shuttles has upon it a T-head N, which can be slid to and fro through correspondingly-shaped notches in the front face of the blades M.

O O are the pusher-rods for passing the 90 shuttles through the sheds in the two sets of ground-warps. The acting end of each rod

is formed with a barbed head O' of a width greater than its thickness and with a projecting flange O^2 in rear of this head. Each end of the shuttle-case is formed with a hole 5 through it, through which the head O' can pass freely, but not the flange O^2 .

Inside each end of the shuttle-case are two spring-catches O^3 . The heads O' of the pusher-rods can when turned into one position pass 10 freely in either direction between the spring-catches; but if a quarter-turn be given to the rod the spring-catches have to give way when the barbed head is pushed forward between them, and the barbed head cannot be withdrawn when drawn back in the opposite direction.

When a shuttle is at one side of the loom and is to be passed across to the opposite side, the flange O^2 of a pusher comes against the end 20 of the shuttle and pushes the shuttle half-way across the loom. Here its opposite end encounters the barbed end of another pusher, which pushes aside the spring-catches O^3 at that end of the shuttle, and the catches then 25 close together in rear of the head. When the two pusher-rods are drawn back away from one another, this last pusher-rod draws the shuttle along with it, as the shuttle cannot escape from its head. The other pusher-rod, 30 which before was pushing forward the shuttle by its flange O^2 , can be drawn back freely, as its barbed head is in such a position that it can be drawn back freely without engaging with the catches O^3 , which are at that end of 35 the shuttle. The last half of the movement of the shuttle is thus effected by the second pusher drawing it along with it, and a heavy tension can thus be maintained upon the weft for as long as may be required.

40 The pusher-rods are actuated in the following manner: The two pusher-rods at each side of the loom are at their outer ends both coupled to a slide P , which can be slid to and fro along fixed guide-rods Q . The connections between the pusher-rods and the slide are such that the pusher-rods can have a partial turn given to them, but are moved endwise when the slide is moved in either direction. The slide is moved to and fro by its 45 being coupled to one end of a lever R , the opposite end of which can turn on a pivot R' . (See Fig. 1.) In the arm is a slot R^2 , into which enters a crank-pin R^3 on a disk fixed to a vertical axis R^4 , so that the arm can be moved 50 to and fro by giving one complete turn to this axis, and each time that the axis makes one complete turn the pusher-rods at the two sides of the loom are made to move inward across the loom toward one another and are 55 then drawn back again. To give a complete turn to the axis R^4 at the times when the movements have to be made, the axis R^4 is geared with a second axis R^5 , upon which is a toothed wheel R^6 . This toothed wheel is 60 acted upon by pegs R^7 , which project out

from a disk R^8 on the shaft E , which receives a continuous revolving movement through gearing actuated from the driving-shaft of the loom. Whenever these pegs come around to act upon the toothed wheel R^6 , they give 70 a half-turn to this wheel, and this movement gives a complete turn to the axis R^4 .

When both sets of pusher-rods have been drawn back into the position shown in Fig. 3, heads formed upon their outer ends enter and 75 fit into sockets S (see Fig. 3) upon short axes S' , which are in a line with them. The short axes S' , which are in a line with the two pusher-rods at each side of the loom, are geared one with the other by toothed wheels 80 S^2 , so that if a partial turn is given to one the other also has a partial turn given to it. To give to them this partial turn, one of them is made to gear with a toothed wheel S^3 on an axis S^4 . (See Figs. 1 and 2.) On this axis is 85 a lever S^5 , the two arms of which are acted upon alternately by a pin S^6 , projecting from one of the heddles F , used for raising and lowering the pile-warps, so that when this heddle is raised or lowered a quarter-turn is 90 given to the axis S^4 , and so a quarter-turn is given to each pusher-rod. Thus after each outward movement of the pusher-rods each pusher-rod has a quarter-turn given to it, and the pusher-rods which were drawing 95 shuttles along with them are turned into a position in which their heads are free to disengage themselves from the shuttle, while the pusher-rods on the opposite side of the loom are turned into a position such that their 100 heads will engage with the shuttles when the shuttles are pushed onto them.

What we claim is—

1. The combination of the shuttle, the spring-catches on the opposite ends thereof, 105 the pusher-rods on opposite sides of the loom in line with each other, the barbed heads on the pusher-rods adapted to engage the catches on the shuttle, the enlargements on the rods in rear of the heads, means for simultaneously moving the pusher-rods toward each other and for causing the shuttle carried by one of the rods to be transferred to and become locked with the other rod, means for then drawing back the rods, and means for 110 giving a partial turn to the pusher-rods when their backward movement has been completed.

2. The combination of the pusher-rods O the slides P to which they are coupled, the lever-arms R to which the slides are coupled, the crank-pins R^3 entering slots in these arms, the axes R^4 carrying these crank-pins, the axes R^5 with which the axes R^4 are geared, the pinions R^6 fast on the axes R^5 , the pegs 115 R^7 acting on these pinions, the disks R^8 to which they are fixed, the revolving shaft E which carries the disks, the sockets S with which the outer ends of the pusher-rods engage when their backward movement has 120 125 130

been completed, and means for then giving a partial rotation to these sockets.

3. The combination of the pusher-rods O, means for moving them endwise toward and 5 away from one another, the sockets S with which the outer ends of the pusher-rods engage when their backward movement has

been completed, and means for then giving a partial rotation to these sockets.

OWEN BULLOCK.

WILLIAM HENRY FORTY.
